US00D815115S

(12) **United States Design Patent** (10) Patent No.: **US D815,115 S**
(45) Date of Patent: **** Apr. 10, 2018**

(54) **DISPLAY SCREEN OR PORTION THEREOF WITH GRAPHICAL USER INTERFACE**

(71) Applicant: **salesforce.com, inc.**, San Francisco, CA (US)

(72) Inventor: **Adrian Dieter Rapp**, Sausalito, CA (US)

(73) Assignee: **salesforce.com, inc.**, San Francisco, CA (US)

(**) Term: **15 Years**

(21) Appl. No.: **29/589,774**

(22) Filed: **Jan. 4, 2017**

(51) LOC (11) Cl. **14-04**

(52) U.S. Cl. USPC **D14/485**

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost dashed broken lines in the FIGURE show a display screen or portion thereof, and form no part of the claimed design.

The dot-dash broken lines in the FIGURE and the white area within the dot-dash broken lines show portions of the graphical user interface that form no part of the claimed design.

1 Claim, 1 Drawing Sheet
